UNITED STATES PATENT OFFICE

2,509,102

VERTICALLY ADJUSTABLE BACK FOR CHAIRS.

Carl J. J. Kuebler, Evansville, Ind.

Application April 1, 1948, Serial No. 18,402

5 Claims. (Cl. 155—157)

1

This invention appertains to novel and useful improvements in chairs.

An object of this invention is to selectively raise and lower the back portion of an otherwise conventional chair and maintain the back portion in the selected raised or lowered position.

Another object of this invention is to provide improved means for carrying out the above mentioned function.

A still further object of this invention is to provide a pair of gears for cooperation with a pair of racks, which racks are rigidly secured to the side members of the chair and which racks have slots therein for accommodation of pins, which pins are in turn secured to the sides of a chair, the gears being engageable with the racks for raising and lowering the back portion of said chair.

A still further object of this invention is to provide ratchet gears movable with the said first-mentioned gears and manually operative means for urging the said ratchet to selected position, locking the ratchet in the said selected position and then returning the said ratchet when it is found desirable.

Another object of this invention is to provide a simplified device of the character described for performing various adjustments on chair backs.

Ancillary objects and features of novelty will become apparent to those skilled in the art, in following the description of the preferred form of the invention, illustrated in the accompanying drawings, wherein:

Figure 1 is a perspective view of the mechanism utilized in association with and forming a part of the present invention;

Figure 2 is a sectional view taken substantially on the broken line 2—2 of Figure 1 and in the direction of the arrows;

Figure 3 is a sectional view of a typical chair utilized with the present invention;

Figure 4 is an enlarged detail of construction taken substantially on the line 4—4 of Figure 3 and in the direction of the arrows, and;

Figure 5 is a sectional view taken substantially on the line 5—5 of Figure 3 and in the direction of the arrows.

This invention relates to improvements in various types of chairs, particularly articles of furniture for domiciles. The general purpose of the present invention is to raise and lower the chair back with ease and facility by simple manipulation of a handle which is positioned adjacent the arm rest of the chair.

A conventional chair generally indicated at 10 is illustrated having sides 12 (which include the

2

chair base) and a chair back 14. This chair back (see Figure 1) has a pair of rack gears 16 and 18 respectively secured to alternate sides thereof.

Pairs of pins 20, 22 and 24, 26 are supplied on opposite sides 12 of the chair and are received in slots 28 and 30 respectively which are formed in the said rack gears 16 and 18. Screws 19 are passed through holes 21 in the rack gears 16 and 18 and are secured to the back 14 of the chair thereby fixing the rack gears to the back. By the above described structure, it is readily apparent that the chair back may be slidable in a selected orbit of travel by means of the pins cooperating with the said slots. Further, the rack gears 16 and 18 are maintained in place through the utility of brackets or guides 32 having substantially U-shaped portions 34 clampingly engaged with the said rack gears 16 and 18. The brackets 32 are fastened by screws or the like to the sides 12 of the chair.

A shaft, preferably square, is illustrated at 36 and has bearings 38 and 40 respectively secured to opposite ends thereof. These bearings are adapted to seat in the structure of the sides 12, 25 for reciprocation of the said shaft 36. A handle 42 is secured to the said shaft 36 adjacent one end thereof and it is desirable that the said handle terminate in a convenient position for actuation from within the chair 10.

A pair of eccentric links 44 and 46 respectively are secured to the said shaft 36 and have pitman rods 48 and 50 respectively provided with bifurcated ends 52 and 54 respectively which are secured to said eccentric links 44 and 46. The said pitman rods 48 and 50 are guided in their travel by means of guides 60 which are secured to the said sides 12 of the said chair construction 10.

Bifurcations 64 are supplied at the free end 40 of the said pitman rods 48 and 50 in order to pivotally receive a dog 66 in each set of bifurcations. The said dogs 66 cooperate with ratchet gear 68 which are secured to a square shaft 70. Said square shaft 70 is journaled in the said sides 12 of the chair construction 10 by means of bearings 72. These bearings are, of course, secured to the terminal portion of the said shaft 70 and are maintained in place by means of conventional nuts 74. Relatively large gears 76 and 78 respectively are secured to the said shaft 70 and are enmeshed with the racks 16 and 18. It may now be seen that by rotation of the said gears 78 and 76, the racks 16 and 18 will be raised and lowered, thereby raising and lowering the back 14 of the said chair.

The dogs 66 aforementioned, engage the teeth

of the ratchet gear in the reciprocatory movement of the pitman rods 48 and 50. By this means, the ratchet gears 68 are rotated, thereby rotating the shaft and effecting the proper desired rotation of the said gears 76 and 78. In order to maintain the ratchet gears and consequently the back 14 of the said chair construction in the desired position, a keeper 80 is secured to the said sides 12 by means of a conventional screw 82. This keeper is juxtaposed relative to the teeth of the ratchet gear 68 and is adapted to engage these teeth until acted upon by an outside force. The outside force in this instance are the protuberances 84 and 86 respectively which are formed integral with the said pitman rod 48. Upon manipulation of the handle 42 and consequent reciprocatory movement of the pitman rods 48 and 50 respectively, the ratchet gears 68 are moved tooth by tooth, thereby lifting the back of the chair. However, when it is desired to return the chair to the relatively low position, the handle 42 is actuated a relatively great amount until the protuberances 84 and 86 operatively engage the keepers 80, thereby pivoting them in an out-of-contact relation with the teeth of the said ratchet gears. This of course, permits the weight of the back 14 to return the same to the lowermost position.

It will be noted that the keeper 80 constantly engages the teeth of the ratchet gear 68 during the normal raising of the chair back 14. However, upon an unusual amount of turn of the shaft 36 in the selected direction, the keepers 80 will be rendered in out-of-contact relation with the teeth of the said ratchet gears.

Having described the invention what is claimed as new is:

1. A chair having sides and a back, racks secured to said back and having longitudinal slots, means associated with said racks for raising said back and maintaining it in selected positions and for lowering the back, said means including a shaft journalled in the sides, a gear journalled on one of the sides and enmeshed with one of said racks, a pitman, means for eccentrically securing the said pitman to said shaft, a ratchet gear movable with said gear, means on said pitman adapted to engage said ratchet gear, a dog pivoted to one of said sides and engaging said ratchet gear, and means secured to said sides for slidably journalling said racks in said slots.

2. A chair having sides and a back, racks secured to said back and having longitudinal slots, means associated with said racks for raising said back and maintaining it in selected positions and for lowering the back, said means including a shaft journalled in the sides, a gear journalled on one of the sides and enmeshed with one of said racks, a pitman, means for eccentrically securing the said pitman to said shaft, a ratchet gear movable with said gear, means on said pitman adapted to engage said ratchet gear, a dog pivoted to one of said sides and engaging said ratchet gear, means secured to said sides for slidably journalling said racks in said slots, and means connected with said pitman for actuating said dog.

3. A chair having sides and a back, racks secured to said back and having longitudinal slots,

means associated with said racks for raising said back and maintaining it in selected positions and for lowering the back, said means including a shaft journalled in the sides, a gear journalled on one of the sides and enmeshed with one of said racks, a pitman, means for eccentrically securing the said pitman to said shaft, a ratchet gear movable with said gear, means on said pitman adapted to engage said ratchet gear, a dog pivoted to one of said sides and engaging said ratchet gear, means secured to said sides for slidably journalling said racks in said slots, and a protuberance formed on said pitman for actuatingly engaging said dog upon movement of said pitman.

4. A chair having sides and a back, racks secured to said back and having longitudinal slots, means associated with said racks for raising said back and maintaining it in selected positions and for lowering the back, said means including a shaft journalled in the sides, a gear journalled on one of the sides and enmeshed with one of said racks, a pitman, means for eccentrically securing the said pitman to said shaft, a ratchet gear movable with said gear, means on said pitman adapted to engage said ratchet gear, a dog pivoted to one of said sides and engaging said ratchet gear, means secured to said sides for slidably journalling said racks in said slots, a protuberance formed on said pitman for actuatingly engaging said dog upon movement of said pitman, and a handle secured to said shaft adjacent one of said sides for actuating said shaft.

5. A chair having sides and a back, racks secured to said back and having longitudinal slots, means associated with said racks for raising said back and maintaining it in selected positions and for lowering the back, said means including a shaft journalled in the sides, a gear journalled on one of the sides and enmeshed with one of said racks, a pitman, means for eccentrically securing the said pitman to said shaft, a ratchet gear movable with said gear, means on said pitman adapted to engage said ratchet gear, a dog pivoted to one of said sides and engaging said ratchet gear, means secured to said sides for slidably journalling said racks in said slots, a protuberance formed on said pitman for actuatingly engaging said dog upon movement of said pitman, and means secured to said sides for guiding said pitman rod.
